(57) **CLAIM**

The ornamental design for a wristwatch as shown and described.

DESCRIPTION

FIG. 1 is a perspective view of the wristwatch showing the new design;

FIG. 2 is a perspective view thereof;

FIG. 3 is a first side view thereof;

FIG. 4 is a second view thereof;

FIG. 5 is a top view thereof;

FIG. 6 is a bottom view thereof;

FIG. 7 is a front view thereof; and,

FIG. 8 is a rear view thereof.

The broken lines in the drawings represent portions of the wristwatch and form no part of the claimed design.

1 Claim, 4 Drawing Sheets
